(57) **CLAIM**

The ornamental design for a mattress, as shown and described.

DESCRIPTION

1. Mattress

1.1 : TOP PERSPECTIVE VIEW

1.2 : BOTTOM PERSPECTIVE VIEW

1.3 : Front

1.4 : Back

1.5 : Top

1.6 : Bottom

1.7 : Left

1.8 : Right

1.9 : PARTIAL ENLARGED TOP VIEW

1.10 : PARTIAL ENLARGED BOTTOM VIEW

1.11 : PARTIAL ENLARGED TOP PERSPECTIVE VIEW

1.12 : SECTIONAL VIEW

1.13 : SECTIONAL VIEW

The even dash broken lines show portions of the mattress that form no part of the claimed design. The long-dash, short-dash broken lines represent the boundaries of the claim and form no part thereof.

Reproduction 1.12 is an enlarged cross-sectional view taken alarm the center of reproduction 1.9. Reproduction 1.13 is an enlarged cross-sectional view a little bit above the center of reproduction 1.9 at the claimed four circular holes.

1 Claim, 13 Drawing Sheets
